UNITED STATES PATENT OFFICE

HARVEY S. COVER, OF SOUTH BEND, INDIANA

RESPIRATOR

Application filed July 9, 1928. Serial No. 291,189.

My invention in general relates to respirators and more particularly to that class of respirators wherein the filter material is not carried by the face piece.

5 The principal object of the invention is to provide an improved device of the kind described of a novel construction and combination of parts with a view to obtaining the maximum of convenience, comfort and efficiency.

Another object of the invention is to provide a respirator with means whereby a comparatively large quantity of filter material may be incorporated therein with a view to 15 securing higher efficiency in filtering the air and absorbing impurities therein.

A further object of the invention is to provide a respirator of a design and construction particularly adapted to yield a clear 20 space for the eyes, with a view to the wearing of goggles or spectacles when desired.

A still further object is to provide a respirator in the form of a novel combination of helmet and face piece.

25 These and other objects and advantages of the method of construction employed will appear more fully in the hereinafter specification when taken in connection with the accompanying drawings in which,

30 Figure 1 is a perspective view showing my invention as it appears in actual use.

Figure 2 is a similar view of the device as viewed from the front.

Figure 3 is a rear elevation of the device 35 itself.

Figure 4 is a sectional view taken on line 4-4 of Figure 3.

Figure 5 is a sectional view taken on line 5-5 of Figure 4.

40 Figure 6 is a fragmentary sectional detail showing a modified form of an exhalation valve used in my invention.

With more particular reference to the drawings, wherein similar characters of 45 reference indicate corresponding parts in the several views of the preferred form of my invention, A designates the head box or helmet which may be of any desired material 50 but preferably of fabricated material of sufficient flexibility to be worn without discom-

fort. The head box has a top 11, side walls 12, front and back walls 14-15 respectively, and partition 16, which latter provides an upper compartment 17 for the reception of filter material 18 and a lower compartment 19 which fits over the head of the wearer, as shown in Figures 1 and 2.

55 Communicating with the interior of the upper compartment 17, and secured to the partition 16, are flexible tubes 20-21 which are passed through the side walls of the head box and thence fastened over short bent portions of metal tubes 22 which are secured to the inner wall of the face piece B by flanges 23, in this manner air communication between the upper compartment and the interior of the face piece being established.

60 The face piece B is formed or molded from a sheet of flexible material to provide a circumferential wall 24 formed integrally with a front disc like portion 25, having a reinforced projection 26 with a shoulder 27 adapted to be resiliently engaged by a cap 28 having a diaphragm 29 which is fitted over an opening 30 leading to the interior of the face piece. As best shown in Figure 4, the top 31 of the cap has a number of inwardly projecting bosses 32 which serve to confine and prevent excessive movement of the diaphragm.

65 The face piece is in part supported by the flexible tubes 20 and 21 but is retained lightly yet securely against the face of the wearer by the flexible straps 39 which are crimped or riveted to the side walls of the head box at one end and at the other end are perforated to admit the bent sections of the air tubes 22. As shown in Figures 2 and 3, I have provided the face piece with a cut out portion 40 to accommodate the nostrils of the wearer in a manner to obtain an air tight adjustment of the face piece to the face with a high degree 70 of comfort.

75 In the modified form of respirator valve shown in Figure 6, the diaphragm 33 has a central perforation 34 to accommodate the shaft of a bolt 35 about which a coil spring 36 is encircled. By referring to Figure 6 it will be seen that the coil spring, which is confined between the top wall 37 of the 80

cap and a projecting portion 38 on the diaphragm, serves to lightly maintain the latter against a recessed seat 33' formed in the projecting part of the face piece, this form of exhalation valve constituting a variation of the one illustrated in Figures 1 to 5.

The function and mode of operation of my invention has been in part suggested from the foregoing description, but will be made 10 more fully apparent by the following brief explanation:

In many devices heretofore used the filter material was placed immediately within the face piece, the quantity being not only 15 sufficient to assure air sufficiently filtered to guard the wearer against the dangers which contaminated atmosphere might otherwise produce, but in addition proved a source of discomfort to the wearer by adding to the 20 size and the weight of the face piece to a disproportionate degree. In the present invention, I have found the head box, or helmet, adequate for the accommodation of an unusually large quantity of filter material 25 within the upper compartment, while at the same time the weight thereof is supported on the head in a most convenient and comfortable manner. The head box may, in fact, be worn for many hours without discomfort. 30 In such cases where the wearer may be exposed to danger from smoke or poisonous gases, the filtering material, which in the present case is merely shredded jute, may be impregnated with a suitable neutralizing 35 solution.

By inspection of Figures 1 and 2 it will be seen that quite a clear space is provided for the eyes of the wearer, who may make use of goggles of the open or gas tight variety.

40 It will, of course, be understood that during inspiration the air will pass through the filter material in the upper compartment to the tubes and thence to the face piece, the diaphragm within the cap serving as a check 45 valve during inspiration but permitting exhaled air to pass through the perforated cap.

When exhaling, the diaphragm will move forwardly from its seat, permitting the 50 breath to pass through the vent holes 28' of the perforated cap.

Among the various mechanical features adding to the convenience and comfort of the wearer, it will be noted that the face piece is 55 sustained largely by the breathing tubes supported from the head box and connected in air tight manner to the top compartment, the face of the wearer in this way being relieved of pressure or weight. The elastic bands 60 which stretch diagonally from the head box to the short tubes on which they are secured, serve to draw the face piece lightly against the face of the wearer, maintaining an air tight contact with the least possible discom- 65 fort.

This device not only embodies all the advantages of a highly efficient respirator, but also serves as a hat or head covering for protection against the rays of the sun, dust, etc. In addition, since the cubical contents capacity of the filter space in the upper compartment of the head box is many times in excess of that available in the ordinary face piece respirator, a high degree of efficiency in filtration is obtained while a comparatively 70 heavy weight of filter material moistened or unmoistened, may be carried comfortably in the upper compartment, the bottom portion preferably resting on top of the head of the 75 wearer.

It will be understood that the device described and illustrated is susceptible to wide modification and change. For example, the head box or helmet is of a configuration merely typical of that which would, for the purpose of illustration, best set forth the mechanical advantages of the device. In actual practice this helmet may be configured to any pleasing shape. 85

I wish it to be distinctly understood, therefore, changes in the specific details of construction can be resorted to within the scope of the appended claim without departing from the spirit or sacrificing any of the advantages of the invention. 90

What I claim as new and desire to secure by Letters Patent is:

A respirator comprising a head box, a partition dividing said head box into an upper compartment and a lower compartment, said upper compartment being adapted to contain filtering material and being provided with an opening of large area for air intake directly from the atmosphere, said lower compartment arranged to fit upon the head of the user, a face piece, a pair of tube members connected to said face piece and extending in a substantially vertical direction to connect with the front portion of said upper compartment, whereby said tube members serve to maintain said face piece in proper spaced relation with respect to said head box for supporting said face piece in position, an exhalation valve mounted in said face piece and constructed and arranged to open upon exhalation and to close upon inhalation, and elastic members connected to said face piece and the sides of said head box and adapted to aid in maintaining said face piece in contact with the face of the user to permit readily disengaging said face piece from the face of the user without disconnecting the same from said head box. 105

In testimony whereof I have signed my name to this specification. 110
